UNITED STATES PATENT OFFICE

CORNELIS F. M. VAN BERKEL, OF LAPORTE, INDIANA, ASSIGNOR TO U. S. SLICING MACHINE COMPANY, OF LAPORTE, INDIANA, A CORPORATION OF INDIANA.

CLAMP FOR SLICING-MACHINES.

1,277,787.

Specification of Letters Patent. Patented Sept. 3, 1918.

Application filed June 4, 1917. Serial No. 172,634.

To all whom it may concern:

Be it known that I, CORNELIS F. M. VAN BERKEL, a subject of the Queen of the Netherlands, and a resident of Laporte, county 5 of Laporte, and State of Indiana, have invented certain new and useful Improvements in Clamps for Slicing-Machines, of which the following is a specification.

This invention relates to a device for holding material to be sliced by the blade of a 10 slicing machine, and has for its object the provision of a clamp of the character mentioned which shall be of improved construction and more efficient in its operation than 15 similar devices previously known.

The invention is exemplified in the combination and arrangement of parts shown in the accompanying drawings and described in the following specification and it is more 20 particularly pointed out in the appended claims.

In the drawings: Figure 1 is a top plan view of a clamp showing one embodiment of the present invention; Fig. 1^a is a fragmentary section showing details of the 25 clutch collar; Fig. 2 is a front elevation of the clamp shown in Fig. 1, Fig. 3 is a fragmentary top plan view of a modified form of the invention, Fig. 4 is a front elevation 30 with parts broken away of the device shown in Fig. 3, Fig. 5 is a fragmentary elevational view showing the post grip and operating lever therefor, and Fig. 6 is a section on line 6—6 of Fig. 5.

This invention comprises a clamp of the same general character as that shown in Patent No. 1,175,025, granted May 14, 1916, and includes features of improvement over the structure shown in that patent.

Referring first to Figs. 1 and 2 of the drawings, the numeral 10 designates the plate on which the meat, or other substance to be sliced, is held while it is being presented to the slicing knife. At one corner 45 of the plate 10, adjacent the front edge thereof, is an upright post or standard 11 and on the diagonally opposite corner is a second similar standard 12. Surrounding the post 11 is a sliding grip collar 13 which fits 50 the post somewhat loosely. The grip collar 13 is provided with a laterally extending arm 14 on which the clamping bar 15 is mounted by means of a pivot pin 16. The clutch sleeve 13 is provided with an up-

standing portion 17 on the side opposite the pivot 16 which provides a long bearing surface on that side. This arrangement prevents the sleeve from gripping the post 11 when downward pressure is exerted on the pivot pin 16. If pressure is exerted upwardly on the pin 16 the long bearing surface 15 is thrown inwardly away from the post 11 and the sleeve will grip the post and resist upward movement. The upper part of the bearing portion 17 is provided with a forwardly extending finger 18 which overlies the upper edge of the clamp 13 so that when the clamp is tilted upwardly, as shown in Fig. 2, the upper edge of the clamp will come into contact with the lower surface of the finger 18 and thus tilt the grip sleeve 13 to release its hold upon the post and permit the collar to slide upwardly. It will be apparent that if the clamp 15 is held at the angle shown in Fig. 2 and moved bodily in an upward direction, the sleeve 13 will permit such movement since it is held with its vertical sides parallel with the sides of the post 11 under these conditions.

The end of the clamp 15, opposite the post 11, is supported by the arm 19 carried by a sleeve 20 arranged to slide upon the post 12. The movement of the sleeve 20 upon the post 12 is controlled by a handle 21 and a clutch grip 22. The clamp 15 is secured to the forward end of the arm 19 by a bolt 23 which permits pivotal movement of the arm and clamp relative to one another about the axis of the bolt. A member 24, connected to the arm 19 and through which the bolt 23 passes, has a limited swiveling movement about a horizontal axis relative to the arm 19, so that the clamp 15 is free to swing about the horizontal axis extending in the direction of the arm 19. This swinging movement, however, is so limited, that the end of the clamp adjacent the post 11 will not swing downwardly below the position shown in Fig. 2, in which position the finger 18 will bear upon the upper surface of the clamp. It will be apparent, therefore, then when upward pressure is exerted upon the handle 21 and the arm 19, the clamp 15 will assume the position shown in Fig. 2, in which position the clutch sleeve 13 will be free to slide upon the post 11 and the entire device may be raised upwardly simply by upward pressure on the handle 21. In a

similar way, the entire clamp may be moved downwardly by simple downward movement of the handle 21, because the sleeve 13 does not resist downward pressure upon the pivot 5 pin 16, as previously explained.

In operation, when the clamp has been brought into position to contact with a piece of meat 25, or similar material, further downward movement will tilt the clamp 10 about the point of contact with the meat, tending to force the pivot pin 16 upwardly. This will be resisted by the clamp sleeve 13, however, and the result of such downward pressure upon the handle 21 will be to bring 15 the clamping bar 15 firmly into engagement with the piece of meat. The clamp, as thus far described, is all shown in the prior patent referred to.

If a piece of meat to be clamped is of the 20 shape and firm nature of a piece of bacon, for instance, it will be apparent from Fig. 2 that the clamp will first strike the corner of the meat adjacent the post 11. Further downward pressure upon the handle 21 will 25 tend to bring the end of the clamp 15 at the right in that figure into contact with the right hand side of the piece of meat, but it is readily apparent that the greatest pressure will be exerted on the edge of the meat 30 adjacent the post 11 and if the meat is very firm in character, it may happen that the operator will not be able to bring the opposite end of the clamp into contact with the meat at all. To remedy this difficulty, ap- 35 plicant has provided a bar or plate 26 which is pivotally supported on the pin 16 between the clutch sleeve 13 and the end of the clamp 15. The plate 26 is provided with an upwardly extending shoulder 27 the upper 40 surface of which normally extends to a position level with the upper surface of the clamping bar 15, as shown in Fig. 2. In this figure, a portion of the clamping bar 15 is broken away to permit the plate 26 to 45 be seen. The portion of the clamp 15 that has been removed is shown in broken lines. The plate 26 is provided with an extension rod 28 which is provided with an upwardly bent portion 29 which rests upon the upper 50 surface of the end of the arm 19 and forms a finger piece by which the plate 26 may be tilted upwardly about the pivot pin 16.

When the clamp has been brought into the position shown in Fig. 2, the operator 55 may raise the end of the rod 29 and thus force the finger 18 upwardly and release the clamping action of the collar 13 on the post 11. If downward pressure is now exerted upon the handle 21, the pivot pin 16 60 may be tilted upwardly about the point of contact of the bar 15 with the meat until the clamping bar has been brought into a position to contact with the entire upper surface of the meat. The bar 65 19 may then be released which will permit

the clutch sleeve 13 to again clamp the post 11 and further downward pressure upon the handle 21 will cause the bar to exert pressure on the meat along its entire upper surface. It will be apparent that the position of the clamp 13 upon the bar 11 may be adjusted to any desired position and caused to grip the post in this position for releasing the extension rod 29 when the proper position has been obtained. 70

In the form of invention shown in Figs. 3 to 6, inclusive, the manually operated plate 26 is replaced by a bell crank lever 30 pivotally mounted on one side of the bar 15, as shown at 31 in the drawings. One end 80 of the bell crank lever 30 is provided with a cylindrical lug 32 extending between projections 33 and 34 carried by the clutch collar 13. The other arm 35 of the bell crank lever 30 extends to a position adjacent the lower edge of the clamping bar 15 and carries a forwardly extending bar or rod 36 which supports a tripping plate 37 positioned beneath the clamping bar 15 and between the downwardly extending teeth 90 thereof, as best shown in Fig. 6. A notch 38 (Fig. 5) is cut in the bar 15 to permit pivotal movement of the bell crank 30 about the support 31. When the clamping bar 15 has been moved into the position shown in Figs. 4 and 5, the tripping plate 37 will contact with the upper surface of the meat 25 slightly in advance of the teeth of the bar 15. When this occurs the bell crank lever 30 will be thrown upwardly, as shown 100 in broken lines in Fig. 5, and the clutch sleeve 13 will be prevented from gripping the bar 11. This will leave the end of the bar 15 carried by the pin 16 free to tilt upwardly the amount necessary to bring the 105 bar 15 into a horizontal position. This upward movement of the pin 16 will carry the sleeve 13 with it and hence tilt the bell crank lever 30 upwardly at the same time that the clamping bar 15 is swinging downwardly 110 about the pivot 16. This will cause the rod 36 to swing upwardly in its groove 38 and bring the tripping plate 37 into position between the downwardly extending rows of teeth of the clamping bar 15. The parts are 115 so proportioned that when the bar 15 has reached a horizontal position, the plate 37 will be located between the rows of teeth of the bar so that it will no longer interfere with the gripping action of the collar 13 120 which will thus be free to hold the pin 16 from upward movement so that the clamping bar may be made to exert pressure in a horizontal position across the entire upper surface of the meat to be clamped. It will be seen that in this form of the invention, the clamping bar is automatically caused to align itself with the upper surface of the material to be clamped, so that it is not necessary to manipulate the clamping loop 125 130

13 by hand; as is done in the form previously described.

I claim:

1. In a slicing machine, a clamping bar, an upright guide at one end of said bar, means for locking said bar against upward movement along said guide, and means other than said clamping bar for releasing said locking means, said releasing means being operable from a position adjacent the end of said clamping bar opposite said locking means.
2. In combination, a plate for supporting material to be sliced, a clamping bar for securing material on said plate, an upright guide, means adjustable along said guide for holding one end of said bar against upward movement, and a tripping device for said adjustable holding means having its operating portion extended toward the end of said bar opposite said upright guide.
3. In combination, a plate, an upright guide bar positioned adjacent one edge of said plate, a clutch collar mounted to slide upon said guide bar, and arranged to tilt relative thereto into position to grip said guide bar, a clamping bar pivoted to said clutch collar and arranged to exert pressure on said collar to cause it to grip said guide bar, and an operating device movable relative to said clamping bar for releasing said clutch collar to permit movement of said clamping bar upon said guide bar.
4. In combination, a plate for holding material to be sliced, an upright guide bar positioned at one side of said plate, a clutch collar adjustably mounted on said guide bar, a clamping bar carried by said clutch collar and movable relative thereto, means for operating said clutch collar from said clamping bar to release said collar and permit upward movement thereof along said guide bar, and means other than said clamping bar for releasing said clutch collar.
5. In combination, a bar for clamping material to be sliced, a guide for one end of said bar, means for adjustably securing said bar to said guide and for holding said bar against movement in one direction thereon, means for releasing said securing means whenever said bar is held in a given position relative to said guide to permit movement of said bar along said guide, and a separate device for releasing said securing means when said bar is held in a different position relative to said guide.
6. In combination, a plate for holding material to be sliced, a guide bar at one edge of said plate, a clamping bar having one end movably connected with said guide bar, means associated with the other end of said clamping bar for adjusting both ends of said clamping bar, means for holding said clamping bar against movement along said guide bar, and means extending to a position

adjacent the end of said clamping bar opposite said guide bar for releasing said holding means.

7. In combination, a guide bar, a clamping bar, a clutch device for connecting said clamping bar with said guide bar, said clutch device being arranged to hold said clamping bar against movement along said guide bar in one direction and arranged to be rendered inoperative for said holding operation when said clamping bar is in one position relative to said guide bar, and means for releasing said holding means for other positions of said clamping bar.

8. In combination, a plate for holding material to be sliced, a bar for clamping material to said plate, means for holding one end of said bar in adjusted positions relative to said plate, and means controlled from the opposite end of said bar for releasing said holding means to permit arrangement of the angularity of said bar relative to said plate.

9. In combination, a plate for holding material to be sliced, an upright guide at one side of said plate, a clamping bar, means for connecting one end of said clamping bar with said guide, said means being arranged to move freely along said guide in either direction when said clamping bar is held at a given angle relative to said guide and being also arranged to prevent movement of said clamping bar along said guide when said clamping bar is held at a different angle relative to said guide, and means for releasing said connecting device to permit movement of said bar relative to said guide when said bar is at an angle relative to said guide other than that angle first referred to.

10. In combination, a plate for holding material to be sliced, an upright guide bar at one side of said plate, a bar for clamping material to said plate, a clutch device for connecting one end of said clamping bar with said guide bar, means connected with the opposite end of said clamping bar for adjusting said bar upon said guide, and means positioned adjacent the last mentioned end of said clamping bar for controlling said connecting device to permit movement of said clamping bar on said guide bar.

11. In combination, a plate for holding material to be sliced, an upright guide bar at one side of said plate, a clutch sleeve slidably mounted on said guide bar and having a laterally extending projection connected therewith, a clamping bar having one end pivotally connected to said projection to cause said clutch sleeve to resist upward pressure on said clamping bar, means for releasing said clutch sleeve when said clamping bar is held at a predetermined angle relative to said guide bar to permit upward movement of said clamping bar, and an operating device for releasing said clutch sleeve at the will of the operator.

125
130

12. In combination, a plate for holding material to be sliced, an upright guide bar at one side of said plate, a clutch sleeve slidably mounted on said guide bar, a clamping bar connected with said sleeve in a manner to cause said sleeve to grip said guide bar to resist upward pressure exerted upon said clamping bar, and means for releasing said clutch sleeve at the will of the operator and 10 adapted to hold said sleeve in released position while the angle of said clamping bar is changed relative to said plate.

13. In combination, a plate for holding material to be sliced, an upright guide bar 15 at one side of said plate, a clutch sleeve

mounted to slide upon said guide bar and having an arm projecting laterally therefrom, a clamping bar pivotally mounted on said arm and arranged to cause said clutch sleeve to grip said guide bar when upward 20 pressure is exerted upon said clamping bar, and an operating rod for said clutch sleeve extending to a position adjacent the end of said clamping bar opposite said guide bar and arranged to release said clutch sleeve at 25 the will of the operator.

In testimony whereof I have signed my name to this specification on this 2d day of June, A. D. 1917.

CORNELIS F. M. VAN BERKEL.
